ATTORNEY.

UNITED STATES PATENT OFFICE.

PATRICK CULLERTON, OF MANSFIELD, WASHINGTON.

WIRE STRETCHER.

1,415,998.

Specification of Letters Patent. Patented May 16, 1922.

Application filed August 31, 1920. Serial No. 407,132.

To all whom it may concern:

Be it known that I, PATRICK CULLERTON, a citizen of the United States, residing at Mansfield, in the county of Douglas and 5 State of Washington, have invented certain new and useful Improvements in a Wire Stretcher, of which the following is a specification.

This invention relates to pushing and 10 pulling implements, and more especially to stretchers operated on the step by step principle; and one object of the same is to produce an improved fence wire stretcher which is capable of use between posts within the 15 run of the fence or beyond the inmost post when the operator reaches the end of said run.

Another object is to produce a structure which will easily grip the wire and may be 20 easily placed in engagement with a fence post.

Another object of the invention is to produce simple and efficient means for connecting the device to fence posts of various sizes.

25 A still further object of the invention is to generally improve upon wire stretchers of this character by providing a device which will be of extremely simple, durable and inexpensive in construction, one which 30 is efficient and reliable in operation, and well adapted to the purpose for which it is designed.

With these and numerous other objects in view, the invention resides in certain novel 35 features of construction and the combination and arrangement of parts as will be hereinafter fully described and claimed.

In the accompanying drawings:—

Figure 1 is a perspective view of the device showing same attached to a fence post.

Figure 2 is a fragmentary top plan view of the toothed bar used in connection with my device,

Figure 3 is an enlarged fragmentary top 45 plan view of the step by step mechanism used in connection with my device, and

Figure 4 is a detailed fragmentary perspective view of a portion of my device showing the means used for attaching the device to a fence post.

Referring to the drawings by numerals it will be seen that the frame of my device consists of the parallel spaced apart plates 1 which are elongated. At one end of each 55 plate and in the corner thereof the ears 2

are provided for receiving the rivets 3 so as to hold the plates in the spaced apart parallel position as shown in the drawing. Intermediate the ends I have also provided ears 4 so as to receive the rivets 5. At the 60 other end of the plate ears 6 are provided at one corner for receiving the rivets 7. In order to attach the frame to the fence post 8 I have mounted upon each plate a hook 9 which has a substantially triangular shape 65 body portion and has one apex thereof provided with an aperture so that the hook may be pivotally attached by means of a rivet 10 to the plate 1. Extending from another apex of the body portion is the bent finger 70 11 which grasps the fence post as clearly shown in Figure 1 of the drawing. The base of the body portion opposite the pivot point is provided with a plurality of notches 75 12 adapted to engage the pin 13 which is seated within an aperture provided in the ear 14 on the plate 1. Thus it will be seen that these hooks are adjustable so as to fit fence posts of various sizes as the pin may be removed and the hooks adjusted to the 80 proper position. It will also be seen that the weight of the frame will cause sufficient binding action as to hold these pins 13 in their respective apertures in the ears 14.

Slidably mounted between the plates 1 is 85 the bar 16 having the staggered notches 17 in its sides. One end of the bar 16 is provided with a cut away portion 18 having the teeth 19 thereon and a pawl 20 is pivoted in this cut away portion 18 by means of a rivet 90 or bolt 21. This pawl is also provided with teeth 22 so that a wire may be placed between the teeth 22 and 19 and of course as the bar 16 is pulled toward the frame in a manner to be hereinafter described the teeth 95 will bite said wire so as to efficiently hold same in connection with the bar. The harder the bar is pulled the tighter will become the connection of the wire between the teeth.

A lever 23 is formed of two sections, 100 superimposed upon each other and held together by means of rivets or other suitable devices and these sections diverge from each other as shown at 24 and are then bent so as to extend parallel with each other for forming the extensions 25. These extensions 25 are pivoted intermediate their ends as shown at 26 and pawls 27 are pivotally mounted between the extensions 25 upon each side of the pivot point 26 by means of rivets 28 as 110

clearly shown in Figure 3 of the drawing. The inner ends of these pawls 27 are provided with points so as to efficiently engage the staggered teeth 17. Therefore, when the lever is reciprocated, the pawls cause the bar to travel between the plates 1 in a manner which will be clear from a consideration of the drawings. The pawls of course may be manually operated or spring means may be provided if desired in a well known manner.

From the foregoing description, taken in connection with the accompanying drawings, the construction and operation of the device will be readily understood without a more extended explanation. As numerous changes in form, proportion, and in the minor details of construction may be resorted to without departing from the spirit of this invention, I do not wish to be limited to the construction herein shown and described other than as claimed.

Having thus described my invention what I claim as new is:—

1. In a wire stretcher, the combination 25 with a frame comprising a pair of elongated parallel spaced plates, ears provided upon said plates and rivets passing through said ears so as to hold said plate in spaced relation to each other, a bar slidably mounted 30 between said plate, means for causing the progression of the bar in the frame, means

for attaching said bar to a wire, and means for attaching the frame to a post.

2. In a wire stretcher, the combination 35 with a frame, a bar slidably mounted in said frame and provided with staggered teeth in its sides, a second bar formed of a pair of sections superimposed upon each other, said sections provided with portions diverging from each other, parallel extensions 40 extending from the diverging portion, said parallel extensions being pivotally mounted intermediate their ends to the frame, pawls pivotally mounted between said parallel sections for engaging the staggered teeth on the 45 bar, means for attaching said bar to a wire, and means for attaching the frame to a post.

3. In a wire stretcher, a frame, a hook comprising a triangular shaped body portion pivoted at one apex to the frame and 50 provided with notches on the base opposite the pivoted apex, a finger extending from one apex adjacent the notched base for engaging a post, and means for engaging the notched base so as to hold said body portion in an 55 adjusted position.

In testimony whereof I affix my signature in presence of two witnesses.

PATRICK CULLERTON.
